UNITED STATES PATENT OFFICE

HELEN DRYDEN, OF NEW YORK, N. Y., ASSIGNOR TO SHURON OPTICAL COMPANY, INC.,
OF GENEVA, NEW YORK, A CORPORATION OF NEW YORK

DESIGN FOR A METALLIC PATTERN STRIP FOR SPECTACLE FRAMES OR SIMILAR ARTICLES

Application filed November 5, 1931. Serial No. 41,634. Term of patent 14 years.

To all whom it may concern:

Be it known that I, HELEN DRYDEN, a citizen of the United States, residing at New York, in the county of New York and State of New York, have invented a new, original, and ornamental Design for Metallic Pattern Strip for Spectacle Frames or Similar Articles, of which the following is a specification, reference being had to the accompanying drawings, forming part thereof.

Figure 1 is a side elevation of a section of a metallic pattern strip for spectacle frames

or similar articles, showing my new design.

Figure 2 is an enlarged plan view of the same.

Figure 3 is a further plan view of the metallic pattern strip of this invention.

Figures 4 and 5 are sections taken on lines 4—4 and 5—5 respectively, Figure 2.

I claim:

The ornamental design for a metallic pattern for spectacle frames or similar articles, substantially as shown and described.

HELEN DRYDEN.
